UNITED STATES PATENT OFFICE.

JAMES McDANIEL, OF MINNEAPOLIS, MINNESOTA; FANNIE E. McDANIEL EXECUTRIX
OF SAID JAMES McDANIEL, DECEASED.

BOX-CAR UNLOADER.

1,274,571.

Specification of Letters Patent.

Patented Aug. 6, 1918.

Application filed June 9, 1916. Serial No. 102,655.

To all whom it may concern:

Be it known that I, JAMES McDANIEL, citizen of the United States, resident of Minneapolis, county of Hennepin, State of Minnesota, have invented certain new and useful Improvements in Box-Car Unloaders, of which the following is a specification.

The object of my invention is to provide an apparatus by means of which a box car loaded with grain or other similar material in bulk may be easily and quickly discharged of its contents.

A further and particular object is to provide an apparatus for handling the car in which the strain of the load thereon is distributed in such a manner that danger of breakage is eliminated and ease of operation and durability of the apparatus is assured.

Other objects of the invention will appear from the following detailed description.

The invention consists generally in various constructions and combinations, all as hereinafter described and particularly pointed out in the claims.

25 In the accompanying drawings forming part of this specification,

Figure 1 is a vertical sectional view through a box car unloader embodying my invention,

30 Fig. 2 is a transverse vertical sectional view of the same,

Fig. 3 is a view corresponding to Fig. 2, showing the car tilted on its longitudinal axis,

35 Fig. 4 is a side view, showing the car tilted on its transverse and longitudinal axis.

Fig. 5 is a plan view.

40 Figs. 6 and 7 are detail sectional views of the means for holding the car in place on the platform.

In the drawing, 2 represents the frame or base of the apparatus, having carrying wheels 3 upon a track 4. This base is shown as movable so that the apparatus can be adjusted from one dumping pit to another. It may, however, and probably in practice will be constructed of concrete and be stationary. This, however, will be governed by the character and circumstances of the installation.

45 The base is provided with a substantially semi-circular recess 5 having rails 6 therein upon which anti-friction rollers 7 are seated, having their ends mounted in side plates 8. A cradle 9 has a curved under surface 55 corresponding to the curvature of the bot-

tom of the recess in the base and is provided on its lower edge with rails 10 which oppose the rails 6 and form opposite bearings for the rollers 7. Thus the cradle has an anti-friction bearing on the base and as there are a number of these rollers the load on the cradle will be distributed peripherally through the rollers to the base.

The cradle 9 has a rack bar 11 thereon and a worm 12 is mounted on a shaft 13 in said base and has a driving connection 14 with a belt 15 to a motor 16. When this motor is operated, the worm 12 will be revolved to rock the cradle on its transverse axis, and as the cradle is supported peripherally on the anti-friction rollers, the pressure of the load will be sustained entirely by these rollers and be distributed between them.

The cradle has cross timbers 17 at each end thereof and an intermediate beam 17' and on the cross timbers a secondary cradle 18 is supported upon anti-friction rollers 7* corresponding substantially to those previously described and mounted in substantially the same manner. It will be understood, however, that I do not in this case make any special claim to these anti-friction rollers, as they are of common construction and may be varied in many ways to suit the different 85 conditions.

This secondary cradle is provided with a rack 19 meshing with a worm 20 on a shaft 21 having a driving connection through gears 22 and a belt 23 with a motor 24 that is mounted in the frame of the primary cradle to rock therewith when this cradle is moved on its transverse axis. When the motor 24 is started, the cradle 18 will rock on its longitudinal axis, said cradle having peripheral bearings operating in substantially the same manner as described with reference to the bearing of the primary cradle.

Upon the top of the secondary cradle I provide a platform 25 having anti-friction roller bearings 26 on the secondary cradle and provided with track rails 27 for the wheels of the box car 28, said track rails being mounted to coincide with rails 29 on the ends of the base and forming the approaches 105 to the cradles. These anti-friction rollers 26 are mounted in a suitable frame 30 and as shown in Fig. 2, the track rails of this platform are inclined downwardly from the dumping side of the car. On this side of 110

the unloader a beam 31, preferably of metal, is horizontally arranged above the spout 32 which leads to the pit into which the contents of the car are dumped. The beam is positioned to form a rest for the car body when it is tilted to its dumping position. In this beam rods 33 are mounted having bearings for brackets 34 which have arms 35 to drop down at the ends of the box of the car and hold it against longitudinal movement on the track. Collars 36 are secured on the rods by means of which the brackets are held in place and I prefer also to provide shoulders 38 on the brackets to dig into the wall of the beam and take up the strain of the pressure of the box car on the arms 35. I also prefer to provide buffer blocks 40, loosely mounted on the beam 31 and adapted to be placed at intervals opposite the side of the car to contact with the car box when it is tilted and form supports at intervals to sustain the wall of the car against outward pressure.

These blocks are movable back and forth on the beam lengthwise of the car and have comparatively broad bearing surfaces for contact with the car, their adjustment permitting them to be placed where they will not contact with any lateral projection, such as bolts and the like, on the car body, and the surfaces of the blocks provide sufficient area of contact to prevent any danger of crushing or otherwise damaging the sheathing or siding of the car. The proper area of these blocks can be easily determined for sustaining the pressure of the load in the car without damage to the car walls, and a sufficient number of blocks may be provided to insure an ample support throughout the full length of the car wall.

As shown in Fig. 4, the base is provided with stops 40' and 41 in the path of an arm 42 mounted on the main cradle, said arm operating to limit the rocking movement of the main cradle on its transverse axis and the plates in which the anti-friction rollers are mounted have projections 43 on one side thereof for contacting with the arm 42 to regulate the longitudinal movement of the plates supporting the anti-friction rollers and preventing them from accidentally working out of their proper position in the base.

The beam 31, mounted on the auxiliary or secondary cradle, is provided with a depending lug or tooth 41' which, when the car is tilted on its longitudinal axis, will enter a recess 42' provided in the frame of the primary cradle and thereby the load of the car, when tilted on its transverse axis, will be sustained by this lug, relieving the anti-friction rollers of undue pressure which might cause damage or breakage thereto.

In the operation of the apparatus, the car

to be unloaded is moved onto the rail supporting platform, the base being shown in a suitable pit convenient to the dumping position so that the car can be easily moved onto the dumping platform. 70

When this has been done and the arms preventing longitudinal movement of the car put in place, the motor is started for tilting the car laterally on its longitudinal axis, and when the car has been so moved 75 for a predetermined distance the rail platform will slide laterally until the box of the car contacts with the stop carried by the secondary cradle. A considerable portion of the grain or other material will then 80 begin to slide out of the open door of the car and this will continue until the middle portion of the load has been discharged. The operator will then start the machinery for tilting the main cradle on its transverse 85 axis, the car still remaining in its tilted position. This will have the effect of causing the grain or other material in one end of the car to slide down, out through the door, and when the car is tilted in the opposite 90 direction, the grain or other material in the other end of the car will be discharged in a similar manner.

The two cradles are mounted each to rock on an axis that is below and near the center 95 of the car, and the axis of one platform is substantially concentric with the axis of the other. When, therefore, the car is tilted to its extreme point of movement, a substantially equal portion of the weight will be 100 on each side of the center, resulting in more even distribution of the load and less strain on the apparatus.

When the car has been unloaded and the cradles are returned to their normal position, the incline of the track rails supporting the platform 25 will cause the car and platform to move by gravity away from the stop 31 until the rails 27 are again in alignment with the rails 29, when the now empty 105 car can be removed and a loaded one put in place of it.

With this apparatus box cars, particularly those loaded with grain, can be easily and quickly discharged of their contents 115 and by mounting the cradles, both primary and secondary, on the anti-friction rollers, I am able to transfer the load from a single central bearing to a peripheral one where the strain will be so distributed that danger 120 of overloading any part of the apparatus and the breakage resulting therefrom will be entirely avoided.

This apparatus may be movable, as shown, or mounted on a fixed base, if preferred. It may be made of any suitable material, the base when immovable being preferably of concrete, while the cradles may be constructed entirely of metal, or wood reinforced with metal. These, how- 130

ever, are unimportant details in the structure of the apparatus, which may be varied and still be within the scope of my invention.

5. I claim as my invention:

1. The combination, with a suitable base, of a segment shaped cradle having anti-friction peripheral bearings thereon, a second segment shaped cradle having anti-friction peripheral bearings in said first named cradle, said cradles being wholly supported upon their peripheral bearings, track rails supported on said second cradle whereon a box car may be placed, and means for moving said cradles to tilt said car successively on its longitudinal and transverse axes and supports provided at intervals for engaging the side wall of the car and having comparatively broad bearing surfaces and movable to avoid projections on the car.

2. A box car unloader comprising a cradle, segmental in form, having anti-friction peripheral bearings for distributing 25 the load evenly upon its support, a secondary cradle having anti-friction peripheral bearings in said first named cradle, said cradles being wholly supported upon their peripheral bearings, track rails carried by 30 said secondary cradle whereon a box car may be placed, and means for independently and successively operating said cradles to first tilt the car on its longitudinal axis and then on its transverse axis and supports 35 mounted to contact with the side wall of the car for supporting the load thereof when tilted and movable back and forth on the car wall.

3. A box car unloader comprising a primary and a secondary cradle mounted to rock in planes at right angles substantially to one another, a platform mounted on said secondary cradle and having freedom of lateral movement thereon, track rails mounted 45 on said platform and a support or rest carried by said secondary cradle and with which the box car contacts through the lateral movement of said platform, said support having comparatively broad bearing surfaces at intervals thereon adjustable on the wall of the car to avoid lateral projections thereon.

4. A box car unloader comprising a primary cradle mounted to rock in a vertical 55 plane and having anti-friction peripheral bearings, a secondary cradle having anti-friction peripheral bearings on said primary cradle to rock in a vertical plane at right angles substantially to the plane of said primary cradle, and a platform having track rails mounted on said secondary cradle, a beam mounted on said secondary cradle to rock therewith and extending parallel with the car on said platform and adjacent there- 60 to, and bearing blocks adjustable on said

beam and having comparatively broad surfaces for contact with the wall of the car.

5. A box car unloader comprising a primary cradle having peripheral bearings and mounted to rock in a vertical plane, a power 70 operated worm and rack bar mechanism for operating said primary cradle, a secondary cradle having anti-friction peripheral bearings on said primary cradle to rock in a vertical plane at right angles substantially to the plane of said primary cradle, a power 75 operated worm and rack bar mechanism for operating said secondary cradle, and a box car supporting platform having track rails carried by said secondary cradle, and a series 80 of bearing blocks supported by said secondary cradle adjacent to said platform and having broad bearing surfaces for contact with the wall of the car on said platform.

6. The combination, with a base mounted 85 for movement from place to place, of a primary cradle having peripheral bearings in said base to rock in a vertical plane, a secondary cradle having peripheral bearings in said primary cradle to rock in a vertical 90 plane at right angles substantially to the plane of said primary cradle, a box car supporting platform having track rails carried by said secondary cradle, and mechanism for operating said cradles, said platform having 95 anti-friction bearings on said cradle for movement laterally with said track rails when said cradle is tilted, and bearing blocks supported by said cradle and adjustable back and forth adjacent to the car wall and having 100 broad bearing surfaces for contact with the wall, for the purpose specified.

7. A box car unloader comprising a primary cradle mounted to rock in a vertical plane, a secondary cradle having anti-friction bearings on said primary cradle and mounted to rock in a vertical plane at right angles substantially to the plane of said primary cradle, a platform having track rails carried by said secondary cradle and mounted 110 to move laterally therein with the car when said cradle is tilted, and blocks adjustably mounted on said secondary cradle and extending along the side of the car and having comparatively broad bearing surfaces 115 for contact with the wall of the car and supporting said wall against outward pressure when the car is tilted.

8. A box car unloader comprising a primary cradle mounted to rock in a vertical 120 plane, a secondary cradle having anti-friction peripheral bearings on said primary cradle to rock in a vertical plane at right angles substantially to the plane of said primary cradle, a platform having track rails 125 on said secondary cradle and mounted to move laterally therein under the weight of the car when tilted, means carried by said secondary cradle and positioned to contact with the car wall when it is tilted and hav- 130

ing comparatively broad bearing surfaces for supporting the wall of the car against outward pressure, said means being adjustable longitudinally of the car for supporting it at any desired point and avoiding lateral projections thereon.

9. A box car unloader comprising a primary cradle having anti-friction peripheral bearings, a secondary cradle having anti-friction peripheral bearings in said first named cradle, the axis of rotation of one cradle intersecting substantially the axis of rotation of the other cradle, track rails carried by said secondary cradle whereon a box car may be placed, and means for operating said cradles to tilt the car on its longitudinal axis and on its transverse axis and means adjustably mounted at one side of said unloader for engaging the car box when tilted on its longitudinal axis.

10. A box car unloader comprising a suitable frame, a primary cradle, segmental

form, having peripheral bearings in said frame, the axis of rotation of said cradle being near and below the center of the car to be 25 unloaded, a secondary cradle, also segmental in form, having antifriction peripheral bearings in said first named cradle, track rails mounted on said secondary cradle and whereon a box car may be placed, means for 30 rocking said cradles on their bearings to tilt the car on its longitudinal axis and on its transverse axis, said car when tilted having a substantially uniform weight upon each side of its axis, whereby there will be an 35 even distribution substantially of the load on said cradles and means mounted at one side of the unloader and adjustable lengthwise of the car for engaging the car box when it is tilted.

In witness whereof, I have hereunto set my hand this 27th day of May 1916.

JAMES McDANIEL.
